Primary Examiner — Abraham Bahta(74) *Attorney, Agent, or Firm* — Marshall, Gerstein & Borun LLP(57) **CLAIM**

The ornamental design of a tube container for cosmetics, as shown and described.

DESCRIPTION

FIG. 1 is a front, top, and right-side view of a tube container for cosmetics, showing the new design.

FIG. 2 is a front elevation view of the tube container for cosmetics.

FIG. 3 is a right-side elevation view of the tube container for cosmetics.

FIG. 4 is a rear elevation view of the tube container for cosmetics.

FIG. 5 is a left-side elevation view of the container for cosmetics.

FIG. 6 is an enlarged top plan view of the tube container for cosmetics.

FIG. 7 is an enlarged bottom plan view of the tube container for cosmetics; and,

FIG. 8 is a front, top, and right side view of a second embodiment, in which the same tube container has an overcap.

The broken line showing of a cap and the dash-dot-dash lines showing a location for the cap is included for the purpose of illustrating environmental structure and forms no part of the claimed design.
